UNITED STATES PATENT OFFICE.

GEORGE LOCHHEAD, OF LOS ANGELES, CALIFORNIA.

CAPPING MACHINE.

Application filed February 2, 1921. Serial No. 441,845.

To all whom it may concern:

Be it known that I, GEORGE LOCHHEAD, a citizen of the United States, and resident of Los Angeles, in the county of Los Angeles 5 and State of California, have invented a new and Improved Capping Machine, of which the following is a full, clear, and exact description:

My invention relates to a capping machine, and aims to provide a device of this character, more particularly adapted for use in connection with the application of tops to cans.

It is well appreciated that considerable 15 difficulty has been experienced in connection with capping devices now placed upon the market, and suitable for hand operation. This objection is more particularly to be attributed to the fact that it has heretofore 20 been necessary to utilize one machine for each size of can to be capped. Also it has been usually customary to provide two different machines for producing the curling and compressing action necessary to effect 25 a perfect seating of the parts.

With this in view, I have provided a capping machine more particularly adapted for use in connection with the capping of cans, and which is primarily devised with a view 30 of producing a machine capable of being operated by hand for household use, although it is not necessarily limited to this adaptation.

A further object of my invention is the 35 provision of a device of this character which shall be capable of effecting a capping of various sized receptacles.

Still another object of my invention is the provision of a device of the character 40 stated in which it will not be necessary to utilize different machines or elements for effecting a curling and compressing action.

Further objects of my invention will appear in the annexed specification and drawings which latter present one practical embodiment of my invention, and in which;

Figure 1 is a partly sectional side view of a can being covered, and showing my improved machine applied thereto.

Figure 2 is a plan view of the same, and

Figure 3 is a partly fragmentary bottom plan view of the device.

In these views the reference numeral 5 indicates the base of any suitable type, conveniently including retaining elements such

as clamps 6, serving to hold a can 7 to which a cap or cover 8 is to be applied.

Referring now more particularly to my improved construction, it will be seen that the machine preferably includes a handle 9, 60 to the lower end of which a clamping plate 10 is secured, thus forming what might be termed a turret, a bracket 11 having one of its ends extending between the handle 9 and plate 10, and being rotatable with respect to 65 these elements.

The bracket preferably provides a longitudinally extending slot 12, carrying a traveler 13, and a longitudinal movement on the part of this traveler with respect to the 70 bracket may be effected by any suitable means such as a screw threaded rod 14 having one of its ends secured to the traveler, its opposite end preferably providing a handle 15, its body engaging a screw threaded 75 opening formed adjacent the outer end of the bracket.

Thus it will be obvious that the movement desired may be accomplished by rotating the handle 15, which will in turn rotate the 80 rod 14, and this element, by virtue of its engagement with the bracket 11 and traveler 13 will serve to move the latter with respect to the former.

It will also be obvious that the handle 15 85 will serve to provide means whereby the entire machine may be rotated around the elements forming the turret, and to provide means serving to co-operate with the cap 8, to apply the same to its proper position, I 90 conveniently utilize a shaft 16 rotatably supported by the traveler, and carrying elements 17 and 18 serving as a curling and compressing member respectively.

Also it is to be noted that the shaft 16 95 may be shifted longitudinally within the traveler 13 for a purpose hereinafter more fully specified, and to provide means serving to retain the same in the position desired, I 100 conveniently utilize a pawl 19, associated with the traveler 13, in such a manner as to engage a groove formed in the shaft 16.

From the foregoing it will be seen that the cap 8 may be positioned upon the body of the can 7, subsequent to the latters having been secured to the base 5, or, other element utilized for this purpose.

The turret is now positioned in the manner indicated upon the cap 8, and by feeding the traveler 13 towards the cap, it will be 110

obvious that the element 17 will be caused to engage the side edges of this latter member subsequent to which a rotation of the bracket 11 by means of the handle 15 will 5 exert a curling action upon the side edges of the cap 8.

Upon this operation having been completed, a retraction of the traveler 13 may be effected by rotating the handle 15, and 10 upon releasing the pawl 19 it will be obvious that the shaft 16 will drop to a position at which the compressing element 18 will align with the edge of the cap 8.

A re-tightening on the part of the handle 15 will now cause this compressing element 15 to properly engage the side edges of the cap 8, and it will be obvious that upon the bracket 11 being again rotated to the requisite extent, that the capping operation will 20 have been completed, and that an air-tight joint will be formed capable of withstanding a relatively great amount of pressure.

From the foregoing it will be seen that I have provided a capping machine more 25 particularly intended for use in connection with the application of caps to the tops of cans, and which may readily be utilized to advantage by an inexperienced operator, aside from the fact that cans of any desired 30 height may be capped by but a single machine, while the entire device is susceptible of application with the tops of cans of varying circumferences, within limitations. Also by virtue of the elements 17 and 18 being 35 provided as a single unit, it will not be nec-

essary to resort to complicated structure to effect the two operations necessary for the complete capping of the can.

Obviously numerous modifications of structure might readily be resorted to without in the least departing from the spirit of my invention, which I claim as;

As a new article of manufacture, a self-complete manually operable holding crimping and compressing instrumentality for a 45 can-top, said instrumentality comprising merely a can-top-engaging member and a single lever structure pivotally carried by said member and having two separate longitudinal sections, one supported by and slidably adjustable on the other along the 50 length of the lever; said lever structure including a single rotary member with its axis arranged perpendicular to the length of the lever structure and movably held at 55 opposite ends on one of said sections for rotation about its axis and also for adjustment lengthwise of its said axis and integrally carrying separate crimping and compressing peripheral surfaces, one spaced 60 from the other axially of the member, said lever structure further including a member to constitute a handle for manually turning the entire lever structure about the can axis, and means for moving the axis of the rotary 65 member lengthwise of the lever structure while maintaining said axis immovable end- 65 wisedly thereof, the means last-mentioned including such handle member.

GEORGE LOCHHEAD.
